W. K. HODGMAN

FUSIBLE LINK

Filed Feb. 28, 1920

INVENTOR.

Willis K. Hodgman

UNITED STATES PATENT OFFICE.

WILLIS K. HODGMAN, OF TAUNTON, MASSACHUSETTS; EMMA A. HODGMAN EXECUTRIX OF WILLIS K. HODGMAN, DECEASED.

FUSIBLE LINK.

Application filed February 28, 1920. Serial No. 362,067.

To all whom it may concern.

Be it known that I, WILLIS K. HODGMAN, a citizen of the United States, residing at Taunton, in the county of Bristol and 5 State of Massachusetts, have invented new and useful Improvements in Fusible Links, of which the following is a specification.

My invention relates to improvements in fusible links used in automatic sprinklers 10 for extinguishing fires, or in other devices wherein it is desirable to hold certain parts of the mechanism to which they are applied in assembled condition until a predetermined degree of temperature exists in the 15 vicinity of the apparatus and melts the solder uniting the parts of the links.

The objects of my invention are to provide a fusible link of superior efficiency as to both its holding and releasing functions. 20 I attain these objects, in a fusible link of the three piece type embodying the principle of the invention, by employing two opposed plates having relatively shoal transverse channels, substantially rectangular in 25 cross section, which provide a chamber between the plates which is occupied by a fulcrum-block located half and half in each of the plates; thus making a fusible link wherein the bearing surfaces of the fulcrum-block or of the channels, which take the 30 tension normally set up in the link, may be formed so as not only to provide a certain and positive tilting tendency to the fulcrum-block but also to provide means whereby a 35 part of the solder, uniting the parts of the link, being in compression and co-operating with the fulcrum-block will form a substantially solid strut in the plane of tension.

In order that the principle of the invention 40 may be readily understood, I have disclosed a single type or embodiment thereof in the accompanying drawing, in which—

Figure 1 is a side elevation of my link; and Fig. 2, a vertical section on line 2—2, 45 Fig. 1.

Similar numerals refer to similar parts throughout the several views.

My fusible link, as shown in the drawing, 50 is of the three piece type and consists of the duplicate plates 4 and 5, the fulcrum-block 6 and a fusible solder which melts at a predetermined degree of heat. The solder is applied between the opposed sur-

faces of the parts of the link in the usual manner but is not shown in the drawing. 55

Each of the plates is provided, near its outer end, with an aperture 7 to receive one of the parts to be held in assembled condition, shown in the drawing as the end of one of the levers 8 or 9 (shown in Fig. 2, only) of a usual type of automatic sprinkler (not shown).

The inside face of each plate near its inner end is provided with a transverse channel 10, rectangular in section, and with 65 sides perpendicular to the face of the plate.

The fulcrum-block 6 is of slightly less width over all than the width of each channel 10 10 thus being free to tilt and pry the plates 4 and 5 apart when the solder 70 melts, and its edges are grooved or concaved as plainly shown in the drawing. The thickness of the fulcrum-block is twice the depth of each channel so it is normally located half and half in the channels. The 75 object of the concave edges of the fulcrum-block 6 is to provide it with a certain and positive tilting tendency caused by the bearing parts of said edges with the co-operating sides of the channels 10 10 being thus 80 definitely located on opposite sides of the plane of the inside faces of the plates 4 and 5, and of the normal plane of tension which latter I have indicated, in the drawing, by the dotted line $x-x$. 85

Having described the releasing properties peculiar to my fusible link I will now proceed to describe its peculiar holding properties.

Referring to Fig. 2, attention is directed 90 to the two spaces or chambers 11 11 formed because the two opposed channels are out of register or overlap at their ends. These chambers are located between the non-bearing edges of the fulcrum-block 6 (by "non-bearing" edges, I mean the edges which do not have direct contact with the sides of the channels 10 10) and the inclosing walls of the channels 10 10. Normally the chambers 11 11 are solidly full of solder which not 95 only neutralizes the effect of the off-set bearings of the edges of the fulcrum-block 6 with the bearing sides of the channels 10 10, previously described, but also provides a substantially solid strut directly in the plane 105 indicated by the dotted line $x-x$, because the

solder in the chambers 11 11 will, provided the fulcrum-block 6 attempts to tilt, be instantly placed in compression.

When the link is assembled the channels in 5 the plates overlap and the fulcrum block is mounted in that portion of the chamber formed by the overlapped portions of the channels. The fulcrum block, it will be noted, is symmetrical with respect to a plane 10 extending midway the thickness of the block. Hence the fulcrum block may be placed in position with either grooved edge up or down and with either face against the bottom of either channel. The fulcrum block 15 is thus reversible both edgewise and endwise. This is of material advantage in assuring the correct assembly of the link because it is impossible by reason of this symmetrical form of the fulcrum block to place it in the 20 wrong position.

The mass of solder which fills that portion of the chamber formed by the channels not occupied by the fulcrum block forms, as already noted with the block, a solid strut 25 which takes compression. The fusible solder used in these links is subject to "cold flow" under the strain imparted to the links by the levers 8 and 9 or similar elements but in the case of this invention owing to the fact 30 that the bearing edges of the block are seated against the adjacent opposed sides of the channels any tendency to "cold flow" cannot impair the holding quality of the link in the line or plane of the strain thus 35 insuring that the link shall retain its proper operative position until the solder is melted or fused by heat. When this takes place the action is a positive one and insures the quick separation of the links so that they fall apart 40 at once as required.

Having thus described one illustrative embodiment of my invention, I desire it to be understood that although specific terms are employed, they are used in a generic and 45 descriptive sense and not for purposes of

limitation, the scope of the invention being set forth in the following claims:

1. A fusible link comprising two plates, each having a similar transverse channel substantially rectangular in cross section 50 with its bottom parallel to the face of the plate, and a fulcrum block of substantially less width over all than the width of each channel of a thickness substantially equal to the combined depth of the channels, having 55 its edges grooved longitudinally, and symmetrical with respect to a plane midway its thickness, whereby in assembling the link the fulcrum block is reversible endwise or edgewise for positioning in the chamber 60 formed by the channels of the plates placed face to face.

2. A fusible link comprising two plates each having a similar transverse channel substantially rectangular in cross section 65 with its bottom parallel to the face of the plate, the said plates being assembled face to face with the channels overlapping, a fulcrum block of substantially less width than the channels, of a thickness substantially 70 equal to the combined depths of the channels, having its edges grooved longitudinally, symmetrical with respect to a plane midway its thickness, and positioned in that portion of the chamber formed by the overlapped channels with two of its diagonally opposite bearing edges engaging the adjacent opposed sides of the channels, and fusible solder filling the space in the opposed channels not occupied by the fulcrum 75 block and extending between and securing together the faces of the plates whereby when the solder is cold a solid compression strut is formed by the solder and the fulcrum block in the opposed channels and when the solder is melted and the plates forced against the bearing edges of the fulcrum block the plates are positively separated by the rocking of the fulcrum block. 80

WILLIS K. HODGMAN.
